UNITED STATES PATENT OFFICE.

GEORGE ROTTMAN, OF NEW YORK, N. Y.

ENVELOP.

1,348,243.

Specification of Letters Patent. Patented Aug. 3, 1920.

Application filed April 23, 1917. Serial No. 163,774.

To all whom it may concern:

Be it known that I, GEORGE ROTTMAN, a citizen of the United States, and a resident of the city, county, and State of New York, 5 have invented certain new and useful Improvements in Envelops, of which the following is a specification.

My invention relates to envelops and their closing means. One object of my invention 10 is to provide an envelop having a fastening device consisting of a band, which may be made of string, tape, or the like, for holding the envelop closed, and of a simple device for securing the band so that it will fit 15 snugly to the envelop, and have no loose ends hanging from the envelop. The securing means comprises a member slideable on the band for taking it up more or less to adapt it to the envelop under different conditions, and the slideable member is adapted 20 to be hooked or connected with a coöperating member which latter preferably is fixed in position on the envelop. The sliding member is easy to adjust and the securing 25 means as a whole is intended to avoid the annoyance of the fastening devices commonly used. The fastening device is especially advantageous for use on extension envelops.

30 In the drawings forming part of this application,

Figure 1 is an elevation of an envelop embodying my invention in which view, one of the corners is turned back to show the 35 arrangement of the corner reinforcement,

Fig. 2 is an elevation of the upper portion of the envelop with the flap opened.

Fig. 3 is a perspective view of the band and the slideable member for taking up or 40 shortening the band.

Fig. 4 is a sectional view, taken on the line 7—7 of Fig. 3.

Figs. 5 and 6 are plan views of the front and back of an envelop having a modified 45 form of closing means.

The closing means shown in Figs. 1, 2, 3 and 4 consists of the following: The band 17 may consist of a piece of string, tape, or any other flexible material adapted for the 50 purpose, the word band being here used to include any such material. There are three eyelets 18, 19, 20 in the flap 16 through which the band is threaded in the manner hereinafter described. A plate 21 secured 55 to the envelop below the lower edge of the

flap has a hook 22 on which the band may be hooked.

On the band there is arranged a sliding member 23 which is intended to shorten or lengthen the band. This member is here 60 shown as a plate folded upon itself and having overlapping ends 24. On one side the plate is formed into a number of reverse loops or folds, 25, 26, 27, 27', 28, 29, 30. The ends of the band are tightly pressed between 65 the walls of the loops 26 and 29 of the plate. Tracing the band from the end held between the walls of the loop 29, it will be observed that it passes around the end of the loop and back between the walls of the loop 30, emerging at the upper end of the sliding member. From the loop 30 the run 31 of the band passes over the flap 16 and through the eyelet 19, thence out through the eyelet 18; from the eyelet 18 the run 32 extends down 70 to the sliding member and the band then passes through the loop 28 of the slideable member. From there the band is drawn out to form a loop 33 for engaging the hook 22. From there the band passes back 75 through the loop 27 of the slideable member to form a run 34, thence over the flap, through the eyelet 18, under the flap, out through the eyelet 20, back over the flap to form a run 35 and finally through the loops 80 25 and 26. The band is tightly held in these latter loops 25, 26.

To lengthen the band ready for attaching it to the hook 22 the loop 33 of the band is 85 grasped in one hand and the sliding member is moved upwardly. This will shorten the runs 31, 35 of the band and permit the runs 32, 34 to lengthen, so that the loop 33 may reach to the hook 22. After the loop 33 is fastened on the hook the runs 32, 34 are 90 grasped in one hand and the sliding member in the other and the latter is moved downwardly on the runs 32, 34. The runs 31, 35 of the band will thus be lengthened, the string being drawn from the runs 32, 34 95 through the eyelets. When the sliding member has been moved down sufficiently the band will be taut enough to hold the flap close on the envelop. The friction on the band where it passes through the loops 27, 100 28 of the sliding member is depended upon to prevent the sliding member from moving except when manipulated as described above. To release the closing device the sliding member is simply moved upwardly or away 105 110.

from the hook 22 and this will shorten the runs 31, 35 and lengthen the runs 32, 34. The loop 33 may then be removed from the hook.

5 The modified device shown in Figs. 5 and 6 differs from the first form in that the band passes around the bottom or extension portion of the envelop. In this form the hook 22 and the sliding member are the same as in 10 the first form and the band is the same as before except that it is longer and that the eyelets are positioned differently. In this form the eyelets 18, 19, 20 corresponding to the eyelets in Fig. 1 are arranged on the 15 front of the envelop just below the hook 22. The runs 31, 35 and 32, 34 of the band pass around the bottom of the envelop, thence over the back and then down over the flap, to the lower edge thereof. I prefer to thread 20 the band through the openings 36 and 37 in the back of the envelop and near the top, in order that the band will remain in place on the envelop. In this form the band and 25 sliding member are manipulated the same as in the previous form except that the runs 32, 34 are grasped between the eyelet 18 and the bottom of the envelop when the sliding member is manipulated. By having the band pass around the bottom of the envelop 30 the latter is prevented from expanding beyond what the contents requires.

Having described my invention, what I claim is:

1. An article of the class described comprising an envelop having a flap, and closing means therefor, said closing means comprising a flexible band, means for engaging the band at spaced positions on the envelop and flap whereby the band will extend across the 35 edge of the flap to hold the flap closed, and 40 slidable means associated with the band for

shortening or lengthening the latter between said engaging means for the purpose set forth, said sliding means having coöperating portions which impinge the band between them to resist the movement of the sliding member on the band. 45

2. An article of the class described comprising an envelop having a flap, and closing means therefor, comprising a flexible band, means for engaging the band at spaced 50 positions on the envelop and flap whereby the band will extend across the edge of the flap to hold the flap closed, said band comprising a plurality of runs, and one of said 55 engaging means including eyelets through which the runs of said band are adapted to slide, a member fixed to certain of said runs and having coöperating portions which impinge other runs of said band between them 60 whereby the slidable member may be moved along said band to tighten or loosen it between said engaging means.

3. A device of the class described comprising an envelop, and means for holding it closed comprising a hook member on said envelop, eyelets on the envelop spaced from said hook member, a flexible band having a plurality of runs slidably engaging in said eyelets, a plate bent to form loops, said band 65 passing back and forth through the loops of said plate and forming a loop 33 for engaging said hook member, said band passing through said eyelets and extending back to said plate and secured thereto, whereby said 70 plate may be slid along certain runs of said band to tighten or loosen the band between said hook member and said eyelets. 75

Signed at the city, county, and State of New York, this 9th day of April, 1917.

GEORGE ROTTMAN.
